UNITED STATES PATENT OFFICE.

VINCENT CECI, OF NEW YORK, N. Y., ASSIGNOR TO SCHMIDT-DAUBER CO., INC., OF NEW YORK, N. Y., A CORPORATION OF NEW YORK.

DESIGN FOR A PIANO CASE.

Application filed June 6, 1924. Serial No. 9,810. Term of patent 14 years.

To all whom it may concern:

Be it known that I, VINCENT CECI, a citizen of the United States, residing in the borough of Queens, Queens County, city and State of New York, have invented a new, original, and ornamental Design for a Piano Case, of which the following is a specification, reference being had to the accompanying drawing, forming part thereof.

The single figure of the drawing is a perspective view of a piano case showing my new design.

I claim:

The ornamental design for a piano case, as shown,

VINCENT CECI.
